THOMAS F. MOORE, OF MORRIS PLAINS, NEW JERSEY

HOLE PUNCHING DEVICE

Application filed May 6, 1931. Serial No. 535,443.

This invention relates to a method of and apparatus for sinking pipes or well-holes into the ground for any purpose, as for example, for supporting superstructures, or for removing moisture or water therefrom through the medium of suitable well-points of the class set forth in my Patents Nos. 1,570,697, January 26, 1926; 1,648,587 November 8, 1927; 1,657,684 January 31, 1928; and 1,729,790, October 1, 1929; and also in my pending application Serial No. 464,659, filed June 28, 1930 so that when the water is removed from the soil, the latter may be economically and expeditiously excavated or otherwise prepared for the safe construction or erection of sub-surface or super-surface structures such as subways, underground conduits and foundations for bridges and buildings.

The main object is to provide a more expeditious, economical and efficient method of and apparatus for sinking pipes and well-holes through widely varying soil-strata and to any practicable depth than has heretofore been practiced.

One of the specific objects is to sink a pipe into the ground by means of a mechanical ram or hammer reciprocally movable therein into and out of engagement with an anvil or other abutment on the lower end thereof and preferably by mechanically hoisting the ram to any required height according to the nature or resistance of the soil and then allowing it to drop freely under its own weight and momentum onto the anvil, and at the same time to relieve the parts from excessive shock incidental to the force of impact of the ram upon the anvil.

Another object is to provide means whereby a second pipe or casing surrounding the driven pipe may be sunk simultaneously with and by the same force as the driven pipe and to utilize the second pipe as a means for conducting water or other material from the top downwardly around the driving point of the inner pipe for jetting or other purposes, or, the outer casing may remain in the ground after the inner tube has been withdrawn, to be filled with concrete and serve as a support for a superstructure.

A further object is to provide simple and efficient means whereby the inner pipe may be withdrawn upwardly from the ground or from the outer casing by the same hoisting device used for the operation of the mechanical ram. 55

Another object is to provide releasable means for locking the head of the outer casing to the head of the inner guide tube or pipe so that both pipe sections may be simultaneously withdrawn from the ground by the same hoisting device when desired. 60

Other objects and uses relating to various parts of the apparatus or to various steps in the process of using the same will be brought out in the following description. 65

In the drawings:—

Figure 1 is an elevation of an apparatus for carrying out the objects of the invention, the central portion being broken away, said apparatus being shown in its initial position as just beginning its entry into the ground. 70

Figure 2 is a longitudinal vertical sectional view of the same apparatus, partly broken away, taken in the plane of line 2—2, 75 Figure 1, except that it is shown as driven a predetermined distance into the ground.

Figures 3 and 4 are transverse sectional views taken, respectively, on lines 3—3, and 4—4, Figures 1 and 2. 80

Figure 5 is a side elevation of the upper portion of the same apparatus, partly in section, showing the hoisting cable in position for withdrawing the entire apparatus upwardly from the ground and also for withdrawing the inner guide tube with a ram and anvil from within the outer casing when the dogs carried by the head of the guide tube are released from engagement with the head of the casing. 85

Figure 6 is a transverse sectional view taken in line 6—6, Figure 2. 90

As illustrated this apparatus is adapted to be hoisted by any suitable means to an upright position with its lower end engaging the ground at the point where it is to be sunk to form the well-hole, and comprises outer and inner pipe sections 1 and 2 telescopically arranged one within the other, an anvil 3 secured to the lower end of the inner pipe 100

section 2 and a mechanical ram or hammer 4 reciprocally movable vertically within the inner pipe section into and out of engagement with the anvil, together with releasable means 5 for locking the pipe-sections to each other against relative endwise displacement one from the other, and means for introducing water or other fluid into the outer pipe section or casing for jetting purposes.

- 10 The pipe sections 1 and 2 may be of any desired diameter or length capable of being driven the major portion of their lengths into the ground to the depth required for permitting the removal of moisture therefrom 15 through the holes formed by the pipes, or for any other purpose for which the well-holes may be made, the upper ends of both pipe sections being allowed to project above the surface of the ground after their lower 20 ends have been driven to the required depth through strata of the same or different soils.

The inner pipe 2 is preferably of greater length than the outer pipe or case 1 into which it is inserted from the top downwardly 25 while both sections are lying in a more or less horizontal position upon or near the surface of the ground or before being hoisted to their upright positions preparatory to entry into the ground so that both ends of 30 the inner pipe section may normally extend beyond the corresponding ends of the outer case.

The anvil 3 is preferably made of solid metal and is provided with a reduced upper 35 end 3' adapted to be inserted into the lower end of the inner pipe section 2 and welded or otherwise permanently secured thereto to move therewith, the lower end of the anvil being provided with a tapered driving point 40 5 of hardened steel or equivalent material having its upper end 5' reduced in diameter and inserted into a corresponding socket 6 where it is held in place by a rivet or bolt 7 or equivalent fastening means.

45 The upper end of the inner pipe section 2 is provided with a tubular head or collar 8 welded or otherwise permanently secured thereto and having its lower end provided with a central co-axial socket 9 for receiving the upper end of the outer casing 1 and a suitable packing, presently described.

The inner pipe section 2 forms a tubular guide for the mechanical ram 4 and is open at the top to permit said ram to be reciprocated vertically therethrough into and out of contact with the upper end of the anvil 3.

The lower end of the collar 8 is also provided with an outturned annular flange 10 having diametrically opposite slots 11 open at 60 the periphery thereof for receiving a pair of pawls or dogs 12 whereby the two pipe sections may be locked to each other when desired, for a purpose hereinafter described.

The outer pipe or casing 1 is of relatively 65 larger diameter than the inner pipe 2 to form

an intervening space 13 into which water or other fluid under pressure may be introduced and allowed to discharge in the lower end thereof for jetting purposes to facilitate the entrance of both pipes into the ground. The 70 casing 1 is provided with a head or collar 14 welded or otherwise rigidly and permanently secured thereto just below the upper end thereof to form an abutment against which the head 8 of the inner pipe section 2 is adapted to impinge for forcing the casing downwardly simultaneously with the downward movement of the inner pipe section by the action of the ram 4 against the anvil 3.

The upper end of the head 14 is provided with an annular flange 15 having an upwardly tapered peripheral surface 15' for automatically deflecting the lower ends of the pawls 12 outwardly as the inner pipe section carrying the head 8 is lowered within the outer casing, and thus permitting the pawls to automatically engage the lower face of the flange 15 when registered therewith, as shown more clearly in Figure 2, the lower ends of the pawls being beveled outwardly and downwardly at 12' to ride against the bevel face 15', and thereby to further facilitate the automatic interlocking engagement of the pawls with the underside of the flange 90 15.

The upper end of the outer casing 1 is provided with a flexible packing collar 16 of rubber or rubberized fabric secured by rivets 16', or equivalent fastening means, to the periphery of said casing just above the collar 14 and adapted to telescopically engage the walls of the chamber 9 in the lower end of the head 8 to form a water and gas-tight joint therewith, aided by the outward pressure of the water or other fluid which may be introduced into the chamber 13 between the pipe sections 1 and 2.

The lower portion of the collar 14 and adjacent portion of the casing 1 are provided with registering fluid inlet openings 17 preferably inclined downwardly and outwardly and connected by a flexible supply pipe or hose 18 to any available source of fluid supply under pressure, the object of which is to introduce this fluid under pressure into the chamber 13 and allow it to escape from the lower end of the casing for jetting purposes.

The heads of the rivets 16' are allowed to project inwardly beyond the inner surface of the outer casing 1 to form guides for centering the inner pipe 2 within the outer casing, and thereby holding the pipe sections in spaced concentric relation to form the chamber 13.

The ram 4 is preferably of appreciably smaller diameter than the interior diameter of the inner guide tube 2 so as to reciprocate freely therein without excessive friction and may be of any suitable length or weight, but 120 125 130

preferably consists of a vertically elongated cylindrical steel rod or bar capable of driving both of the pipe sections into the ground under its own weight and momentum after having been lifted to a predetermined height and allowed to drop under its own weight.

The upper end of the mandrel 4 is provided with a vertical slot 4' for receiving a clevice or link 19 having its lower end attached to a bolt 20 on the adjacent portion of the ram 4, and its other end connected by a cable 21 to a suitable hoisting device, not shown, for the reason that any suitable hoisting device may be used for lifting the ram 4 to any desired height and then releasing it to allow it to drop through the inner pipe 2 onto the anvil 3.

It is now evident that as the ram 4 is lifted to a predetermined height and then allowed to drop freely, its impact against the anvil 3 at each descent will cause the inner pipe 2 to be driven a greater or less distance into the ground, depending somewhat upon the nature of the soil, and also upon the distance through which the ram is allowed to fall.

This downward driving movement of the inner pipe section is transmitted to the outer casing 1 by the engagement of the lower end of the head 8 with the upper end of the head or collar 14, and while these heads 8 and 14 are made of cast iron, steel or other strong and durable material, it is evident that the contacting ends would soon become battered or unduly worn unless some provision is made for reducing the shock incidental to the impact of the ram against the anvil.

For this latter purpose a pair of U-shaped yokes 22 are hingedly connected by pivotal pins 23 to suitable lugs 24 on diametrically opposite sides of the upper portion of the head 8 to extend downwardly from their respective pivots toward, but in spaced relation to, the annular flange 10 in alignment with the corresponding pawls 12.

These pawls 12 are slidable vertically in their respective guide slots 11 and are provided at their upper ends with reduced spindles 25 extending through suitable openings 26 in the lower ends or cross bars of the corresponding yokes 22 substantially radial to and just below the adjacent pivotal pins 23, as shown more clearly in Figures 1 and 2.

The portions of the pawls 12 near end junctions with the spindles 25 are provided with shoulders 22' against which the lower ends of the yokes 22 are adapted to rest, the upper ends of the spindles 25 being threaded and engaged by nuts 27, as shown in Figure 2.

Each of the spindles 25 is surrounded by a coil spring 28 having its upper end engaged with the underside of the nut 27 and its lower end engaged with the cross bar 26 of the yoke 22, thereby establishing resilient connections 29 between the heads 8 and 14 normally urging

the heads into contact with each other but still permitting said heads to separate against the action of the springs.

For example, during each descent of the ram 4 upon the mandrel tending to drive the inner pipe 2 and its head 8 downwardly, the shock, due to the impact of the head 8 of the inner pipe 2 against the upper end of the head 14 of the outer casing 1, will be at least partially offset by the resultant compression of the springs 28 due to the fact that under those conditions the head 8 and its yokes 22 may exert an upward pull upon the springs, or the lower head 14 and pawls 12 may exert a downward pull upon the same springs, thus reducing the shock incidental to each percussion blow the the ram upon the anvil and incidentally avoiding undue impairment of the contacting ends of the heads 8 and 14, and also reducing the shock upon the supply pipe 18 and its connection with the head 14 to avoid impairment thereof.

During this relative axial movement of the heads 8 and 14, the packing flange 16 and walls of the socket 9 are free to slide one upon the other, the lower end of the walls of the socket 9 being beveled at 9' to permit the head 8 to slide freely over the packing flange when assembling the pipe section 2 within the outer casing 1.

If desired, suitable washers may be placed between the ends of the springs 28 and nuts 27, or between the lower ends of the spring and adjacent wall of the yokes 22.

The pawls 12 are movable about the axes of their respective pivots 23 and 23 into and out of engagement with the lower faces of the flange 15 of the head 14 for connecting and disconnecting the inner and outer pipe sections, and are normally spring-pressed inwardly toward each other or into engagement with said flange 15 by springs 30 which are coiled around the outer ends of the corresponding pivotal pins 23 with one end engaged with the head 8 and its other end engaged with the adjacent pawls, as shown more clearly in Figures 1, 3 and 5, the object being to cause the pawls to automatically engage the flanges 15 when the inner pipe section is inserted from the top downwardly into the outer casing 2.

The head 8 is provided near its upper end with a laterally projecting boss or lug 31 having a convex lower face and an end flange 32 for receiving a portion of the cable 21, as shown in Figure 5, whereby the hoisting cable used for raising the ram 4 may also be used for withdrawing the inner pipe section 2 upwardly from the outer casing 1 when the dogs or pawls 12 are disengaged from the flange 15.

Or, when the dogs 12 are engaged with the flange 15 on the head 14 of the outer casing 1, the same hoisting device, after being passed around the underside of the lug 31, may be

- used for withdrawing both of the pipe sections 1 and 2 from the ground without detaching the cable from the upper end of the ram, it being understood that after the pipes 5 have been driven to the required depth into the ground, the dogs 12 may be readily operated by hand or otherwise for engaging or disengaging the flange 15 and that in like manner the cable 21 may be placed by hand 10 or by manipulation of the hoisting mechanism around the underside of the lug 31, or removed therefrom as may be desired.

Operation

- 15 When it is desired to sink a well-hole or to drive one or both of the pipe sections 1 and 2 into the ground, these pipe sections may be assembled in the manner shown in Figure 1 and the entire apparatus then hoisted to 20 an upright position through the medium of the cable 21 and lug 31 with its lower end resting on the ground at the point where the hole is to be made.
- The entire apparatus is then steadied in 25 an upright position by any suitable means aided by the cable 21 and hoisting device during which operation the pawls 12 will be brought into interlocking engagement with the flange 15 of the inner pipe section 2 as 30 the outer casing is placed telescopically over and upon the inner pipe section.

The cable 21 which is then disengaged from the lug 31 will then be drawn upwardly to cause a corresponding lifting movement of 35 the ram 4, after which the cable is released to allow the ram to descend into engagement with the anvil 3, thereby driving the inner pipe and outer casing downwardly a distance somewhat proportionate to the drop of the 40 ram and also the resistance of the soil.

This operation of the ram is repeated with gradually increasing distances of drop until the pipe sections are sunk to the required 45 depth, during which operation water or other fluid under pressure may be introduced into the chamber 13 through the inlet 17, and allowed to escape at the bottom of said chamber for jetting purposes, and thereby to expedite the operation of sinking the pipes into 50 the ground.

It is to be understood, however, that the outer casing 1 may be omitted, if necessary or desirable, in which case the inner pipe section could be driven into the ground to any 55 required depth by repeated operation of the ram 4 against the anvil 3.

It has been found, however, that the use of the outer casing 1, in connection with the inner pipe section 2, is desirable in that it provides a means for supplying water or other fluid under pressure to the bottom of the hole around the anvil 3 for expediting the sinking 60 operation.

When the inner pipe is sunk to the required 65 depth and it is desired to withdraw the same

from the hole formed thereby, the cable 21 may be passed around the underside of the lug 31 and then drawn upwardly by any suitable hoisting device to effect a corresponding upward withdrawal of the inner pipe, irrespective of the outer casing, in which case it is simply necessary to withdraw the locking dogs 12 from engagement with the shoulder 15 of the outer casing.

If, however, the outer casing has been driven into the ground simultaneously with the inner pipe section, both the casing and the inner pipe section may be similarly withdrawn from the ground by leaving the locking dogs 12 in engagement with the flange 15 80 and then passing the cable 21 around the underside of the lug 31, after which the cable may be raised to effect a similar upward withdrawal of the apparatus from the ground leaving a substantially clean hole into 85 which well-points or other devices may be used for withdrawing any sub-surface water from the soil.

Or, on the other hand, after the inner pipe section, together with the ram 4 and anvil 3, 90 has been withdrawn from the ground, the outer casing may remain in the ground to receive concrete or any other material so that the outer casing with its filler may be used for supporting super-structures, or, it may be 95 used to receive a well point for withdrawing water from the hole.

What I claim is:—

1. In an apparatus for sinking well-holes into the ground, separate upright pipes arranged one within the other and adapted to be forced endwise into the ground, the inner pipe being open at the top, an anvil secured to the lower end of the inner pipe, a ram movable through the open upper end of the inner pipe into and out of impact with the anvil for driving the inner pipe into the ground, means for causing both pipes to enter the ground simultaneously under the force of impact of the ram with the anvil, said pipes having portions thereof arranged in spaced relation to form an intervening chamber open at the bottom, and means for introducing a fluid into said chamber to discharge at the bottom around the lower end of the inner pipe.

2. In an apparatus for sinking well-holes into the ground, separate upright pipes arranged one within the other and adapted to be forced endwise into the ground, the upper end of the inner pipe being open, an anvil secured to the lower end of the inner pipe, a ram movable through the open upper end of the inner pipe into and out of impact with the anvil for driving the inner pipe into the ground, a head secured to the upper end of the outer pipe, a head secured to the upper end of the inner pipe and normally engaging the head of the outer pipe for driving the outer pipe into the ground as the inner pipe

is driven downwardly by the ram, and dogs hingedly connected to the head of the inner pipe and movable into and out of holding engagement with the head of the outer pipe for locking and releasing the inner pipe to and from the outer pipe whereby the outer pipe may be withdrawn from the hole with the inner pipe or the inner pipe withdrawn from the outer pipe.

10 In witness whereof I have hereunto set my hand this 28th day of April 1931.
